US00D893117S

(12) **United States Design Patent** (10) **Patent No.:** **US D893,117 S**
(45) **Date of Patent:** ** *Aug. 11, 2020

(54) **ANIMAL LITTER BOX**

(71) Applicant: **KITANGLE, LLC**, Bennett, CO (US)

(72) Inventor: **Kristin L. Olson**, Bennett, CO (US)

(73) Assignee: **KITANGLE, LLC**, Bennett, CO (US)

(*) Notice: This patent is subject to a terminal disclaimer.

(**) Term: **15 Years**

(21) Appl. No.: **29/627,975**

(22) Filed: **Nov. 30, 2017**

(51) LOC (12) Cl. **30-99**

(52) U.S. Cl.

USPC **D30/161**

(58) **Field of Classification Search**

(57) **CLAIM**

The ornamental design for an animal litter box, as shown and described.

DESCRIPTION

FIG. 1 is a front perspective of an animal litter box showing my new design.

FIG. 2 is a front perspective (exploded) of an animal litter box showing my new design.

FIG. 3 is a front view of an animal litter box showing my new design.

FIG. 4 is a rear view of an animal litter box showing my new design.

FIG. 5 is a right-side view of an animal litter box showing my new design.

FIG. 6 is a left-side view of an animal litter box showing my new design.

FIG. 7 is a top view of an animal litter box showing my new design; and,

FIG. 8 is a bottom view of an animal litter box showing my new design.
